INVENTOR
James M. Price,
BY John Adlersheim,
ATTORNEY.

UNITED STATES PATENT OFFICE.

JAMES M. PRICE, OF PHILADELPHIA, PENNSYLVANIA.

STREET RAILWAY OR TRAMWAY.

SPECIFICATION forming part of Letters Patent No. 469,392, dated February 23, 1892.

Application filed December 10, 1890. Serial No. 374,156. (No model.)

To all whom it may concern:

Be it known that I, JAMES M. PRICE, a citizen of the United States, residing in the city and county of Philadelphia, State of Pennsylvania, have invented a new and useful Improvement in Street Railways or Tramways, which improvement is fully set forth in the following specification and accompanying drawings.

10 My invention relates to improvements in street railways or tramways; and it consists in the construction and arrangement of the parts hereinafter set forth.

Figure 1 represents a section of a street-railway embodying my invention. Figs. 2 and 3 represent sectional views of modifications of the same.

Similar letters of reference indicate corresponding parts in the several figures.

20 Referring to the drawings, A designates a street-rail, and B a chair of arched or angular shape, the latter being formed of either rolled, stamped, or cast metal and having flaring sides C, provided with horizontal feet D, extending outward from said chair and adapted to be secured by the spikes E to a wooden or other cross-tie E'.

25 The top of the chair is fitted closely in the under side of the rail, and both sides of the crown thereof are embraced by the depending flanges F of the rail and are provided with openings, through which and other openings in the said flanges F are passed the metallic binding-straps G, which pass underneath the under face of the crown of said chair and have their outer ends bent so as to be held in place.

30 In the modification shown in Fig. 2 a wooden sleeper H, resting upon the cross-ties E', is inserted within a chair J, which is of less thickness than that shown in Fig. 1, so as to strengthen the same and thereby aid in supporting the rail A thereon. The sides of the said chair are provided with openings for the insertion of spikes or rails K, preferably cylindrical in shape, for binding the said chair to the sleeper. Passing through openings in the flanges of the rail A are the spikes, nails, or straps L, which are driven in or rest in 45 grooves on the upper face of the wooden sleeper and directly beneath the under face

of the crown of the chair. The feet of the chair are secured by suitable means to the cross-tie.

In Fig. 3 is shown a section of a channeled chair having the shoulders M on its sides, on which rest the flanges N of the rail, which are lengthened and are of greater thickness than those shown in the other forms. The said chair is adapted to form a continuous passage or channel N'. A soft metallic strap 60 P, passing through the flanges of the rail and the sides of the arch above the shoulders and having its outer ends hammered down outside the flanges binds the rail and chair together, and spikes secure the feet of the chair 65 to the cross-tie.

In the structure shown and described the holes or openings in the flanges and chair are either oblong, oval, or rectangular and of a greater length than height to provide for expansion or contraction of the construction due to heat or cold. In connecting the rails and channel-chairs broken joints are used, so that the ends of the chairs and the rails do not coincide.

70 The chair constructions herein shown are first rolled in lengths of from twenty to forty feet of their respective sections and then sawed into widths of from three to five inches, except the joint-chairs, which rest upon the two cross-ties and which should be from 75 twelve to twenty-four inches long.

The strength of the arched longitudinal chair as first made is such that cross-ties may be entirely dispensed with and an excellent 80 all-metallic structure had without sawing into chairs by resting this arched channel-rail system upon a tamped bed of Belgian block, broken stone, or its equivalent.

85 It will be seen that the various chairs herein described may be made of a channel-bar bent into the shape indicated by suitable rolls or other devices, punched or drilled to form holes, as stated, and sawed transversely, those for the joints being double or treble the length 90 of the ordinary chair.

95 Both the arched-chair and the arched-channel constructions are possessed of great strength and elasticity, and the latter breaking joints with the rails frequently fastened 100 to it makes a very firm and smooth surface, preventing shocks at the joints.

The sleeper may be grooved to the width and thickness of the chairs, so that the top of the sleeper supports the bed of the rail by contact therewith, and spikes or nails may be driven through the openings in the flanges of the rail diagonally into the sleeper, thus making a very solid structure of great strength.

Having thus described my invention, what I claim as new, and desire to secure by Letters Patent, is—

1. A rail having depending flanges with openings therethrough, a hollow chair on which said rail rests, a wooden sleeper in said chair, means, substantially as described, connecting said rail and chair, means, substantially as described, connecting said chair and sleeper, and a cross-tie to which said chair is secured, said parts being combined substantially as described.
2. A metallic chair with rectangular central space inclosing and fitting a wooden longitudinal sleeper, to the sides of which it is spiked through holes in the sides of the chair, while its feet through similar holes are spiked to the cross-tie, upon which sit both chair and sleeper, and a rail on said chair having depending flanges with openings therethrough

to receive a fastening with heads resting against said flanges of the rail, substantially as described.

3. A metallic chair embracing and containing a wooden longitudinal sleeper seated upon cross-ties, and the chair bound to the rail, seated upon it by spikes driven through coincident holes in the depending flanges of the rail and the sides of the chair, the latter bound by spikes laterally to the wooden sleeper embraced and vertically to the cross-ties, substantially as described.

4. A street or tramway rail fastened laterally through its depending flanges to a metallic chair upon which it sits, and to a contained wooden longitudinal sleeper by spikes through suitable holes in both, said spikes having heads resting against said rail-flanges, in combination with the chairs, the sleeper, and the cross-ties upon which the sleeper sits and to which the chairs are spiked, substantially as described.

JAMES M. PRICE.
